US00D575009S

(12) **United States Design Patent**
Murrell et al.

(10) **Patent No.:** US D575,009 S
(45) **Date of Patent:** ** Aug. 12, 2008

(54) **PET COLLAR**

(75) Inventors: **Tara Murrell**, Leawood, KS (US);
Kristin Goodman, Stillwater, MN (US)
(73) Assignee: **Flux, Inc.**, Leawood, KS (US)
(**) Term: **14 Years**
(21) Appl. No.: **29/249,438**
(22) Filed: **Oct. 6, 2006**

(57) **CLAIM**

We claim the ornamental design for a pet collar, as shown and described.

DESCRIPTION

FIG. 1 is a perspective view of a pet collar embodying our new design;

FIG. 2 is a front elevational thereof;

FIG. 3 is a left side elevational view thereof;

FIG. 4 is a top plan thereof;

FIG. 5 is a rear view thereof; and,

FIG. 6 is a right side elevational view thereof.

The shading that indicates texture is intended to describe the whole surface of the band.
